UNITED STATES PATENT OFFICE

DAVID S. JACOBUS, OF JERSEY CITY, NEW JERSEY, ASSIGNOR TO THE BABCOCK & WILCOX COMPANY, OF BAYONNE, NEW JERSEY, A CORPORATION OF NEW JERSEY

FLUID HEATER

Application filed April 10, 1925, Serial No. 22,111. Renewed January 22, 1930.

My invention more particularly relates to a fluid heater wherein provision is made for cleaning the tubes in such a way that the walls of the headers to which the tubes are connected are of maximum strength and adapted to withstand high pressures.

My invention will best be understood by reference to the accompanying drawings in which I have illustrated one embodiment of my invention and in which Fig. 1 is an end elevation of the heater, the left-hand portion of this figure being an elevation of the front part of the heater and the right-hand portion of the figure being a partial view of the headers at the rear end of the heater. Fig. 2 is a side view thereof and Fig. 3 is a section taken along the line 3—3 of Fig. 2, looking in the direction of the arrows.

Like reference characters indicate like parts throughout the drawings.

Referring to the drawings, 10 and 11 are supporting standards for the fluid heater, two standards 10 at one end preferably being provided and connected by a cross bar 12, the supporting standards 11 at the opposite end of the fluid heater being connected by a cross bar 13.

The fluid heater embodying my invention comprises a plurality of headers 14, preferably arranged in two rows 15 and 16, the headers of each row preferably being arranged in parallel relation, and in the form illustrated, the headers are horizontal and arranged one above the other, the headers of one row being staggered with reference to those of the other row. The lowermost header 141 of the row 15 is supported on the standards 10, and adjacent headers are preferably spaced apart, as at 17, a sufficient distance to permit of the removal and insertion of the tubes through these spaces. Suitable blocks 18 are interposed between the header 141 and the next upper header 142, supporting blocks similarly being interposed between successive headers. Similarly, the lowermost header 143 of the row of headers 16 is supported on the standards 11 and the remaining headers are spaced and supported similarly to the headers of the row 15.

Each of the headers, with the exception of the lowermost header 141 of the row 15 and the uppermost header 144 of the row 16 are preferably provided with two rows 19 and 20 of tube openings which are preferably equally spaced apart, and preferably arranged in staggered relation as illustrated in Fig. 1, to form groups 21, 211 and 212, etc., as best illustrated in Fig. 1, each group being in the form shown opposite two tube openings. Each of the headers 141 and 144 are provided with a single row only of tube openings. Tubes 22 arranged in rows, and preferably slightly upwardly inclined, as illustrated in Fig. 2, are expanded at their ends 65 into the tube openings of the headers, the rows of tubes transversely of the fluid heater being connected at their ends to the respective rows of tube openings in the headers. Water or other fluid enters the lowermost 70 heater 141 of the row 15 through the inlet 23 and is distributed therein to the various tubes of the lowermost row through which it flows to the lowermost headers 143 of the row 16, and back and forth through the successive rows of tubes and headers to the outlet header 144, from which it passes through the outlet 24, and when the fluid heater is used as an economizer, the water flows from the outlet to the steam and water drum of 80 the boiler.

My invention makes provision for cleaning the tubes of the fluid heater and, at the same time, forming the headers of the economizer of maximum strength.

By my invention, part of the tubes, preferably one-half thereof, are cleaned from one end of the heater, while the remaining tubes are cleaned from the opposite end thereof, thereby requiring a minimum number 90 of handholes in the headers and preserving maximum strength therein. In the form shown, sufficient handholes only are provided in each header to afford access to alternate groups of tube openings, so that one-half of the tubes are cleaned from one end of the fluid heater and the remaining tubes are cleaned from the opposite end thereof.

Referring to Fig. 1, it will be evident that the tubes 221 and 222 are accessible for clean- 100

ing through the handhole 25 and the tubes 223 and 224 are accessible through the hand-hole 251 of the header 145 of the row 16. Tubes of alternate groups, on the other hand, are accessible for cleaning through hand-holes of the headers at the opposite end of the fluid heater. For example, the tubes 225 and 226 are accessible for cleaning through handholes in the headers at the opposite end 10 of the fluid heater, as indicated in dotted lines in Fig. 1, as are the tubes 227 and 228. The handholes are closed by suitable removable handhole covers as shown in Fig. 2 and one of which is shown in Fig. 3.

15 By providing handhole openings opposite alternate groups of tube openings only, it will be evident that the header is very much stronger than would be the case if sufficient handholes were provided at one end of the fluid heater for affording access to all of the tubes for cleaning purposes. My invention is particularly applicable to an economizer for a steam boiler of the high pressure type, and is particularly useful in an economizer 20 of this type wherein the headers are spaced sufficiently to permit of passage of the tubes therebetween, for it is then particularly important that the header walls should have the maximum strength.

25 It will, of course, be understood that heating gases are caused to flow across the tubes of the fluid heater, and when the fluid heater is used as an economizer, it will preferably be arranged in a flue for the gases similarly 30 to the economizer illustrated in my Patent No. 1,329,767, which issued February 3, 1920, the water in that case preferably flowing through the economizer in a direction generally opposite to the direction of flow of 35 gases across the tubes.

40 I claim:

1. A fluid heater comprising a plurality of headers at each end of the heater, at least some of which are provided with a plurality 45 of rows of tube openings, the tube openings of the rows forming groups, tubes connecting the headers and entering said openings, each header being provided with handholes opposite alternate groups of tube openings, removable handhole covers being provided for said handholes.

2. A fluid heater comprising a plurality of headers at each end of the heater, at least some of which are provided with a plurality 55 of rows of equally spaced tube openings arranged in staggered relation, the tube openings of the rows forming groups, tubes connecting the headers and entering said openings, each header being provided with handholes opposite alternate groups of tube openings, removable handhole covers being provided for said handholes.

3. A fluid heater comprising a plurality of 60 headers at each end of the heater, the headers at one end being staggered with respect to

those at the other end, at least some of which are provided with a plurality of rows of tube openings, the tube openings of the rows forming groups, inclined tubes connecting the headers and entering said openings, the tubes entering the respective rows of openings being connected to adjacent headers at the other end of the heater, each header being provided with equally spaced handholes opposite alternate groups of tube openings, removable handhole covers being provided for said handholes.

4. A fluid heater comprising a plurality of headers at each end of the heater, the headers at one end of the heater being staggered with reference to those at the other end, at least some of the headers being provided with two rows of tube openings extending longitudinally of the header, the tube openings of the two rows forming groups, inclined tubes connecting the headers and entering said tube openings, each header being provided with handholes opposite alternate groups of tube openings, removable handhole covers being provided for said handholes.

5. In a fluid heater comprising headers at least some of which are provided with two rows of tube holes extending longitudinally thereof, tubes connected at their ends to said headers and entering said tube holes, the holes of both rows being equally spaced so that the tubes of one row form groups with those of the other, the headers being provided with handholes opposite alternate groups only of tube holes, removable handhole covers being provided for said handholes.

6. A fluid heater comprising oppositely located headers arranged in rows, tubes connected at their ends to said headers, both rows of headers being provided with handholes, the handholes of one row of headers serving one-half only of the tubes for cleaning purposes and the handholes of the other row of headers serving the other half of the tubes for cleaning purposes, removable hand-hole covers being provided for said handholes.

DAVID S. JACOBUS.
